[57] CLAIM

The ornamental design for a golf putter, as shown and described.

DESCRIPTION

FIG. 1 is a top perspective view of a golf putter showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a right side elevational view of FIG. 1;

FIG. 7 is a left side elevational view of FIG. 1;

FIG. 8 is an enlarged top perspective view of a second embodiment of the golf putter as disclosed in FIG. 1, the shaft shown fragmented for ease of illustrations

FIG. 9 is a rear elevational view of FIG. 8;

FIG. 10 is a front elevational view of FIG. 8;

FIG. 11 is a top plan view of FIG. 8;

FIG. 12 is a bottom plan view of FIG. 8;

FIG. 13 is a left side elevational view of FIG. 8; and,

FIG. 14 is a right side elevational view of FIG. 8.

FIGS. 8, 9, 10, 13 and 14 disclose the shaft broken away due to indeterminate length.
